METHOD OF CONSTRUCTING A CABINET

Original Filed Oct. 9, 1933

UNITED STATES PATENT OFFICE

2,117,082

METHOD OF CONSTRUCTING A CABINET

Leonard H. Darbyshire, Detroit, Mich., assignor
to Borg-Warner Corporation, a corporation of
Illinois

Original application October 9, 1933, Serial No.
692,882. Divided and this application Decem-
ber 28, 1935, Serial No. 56,511

3 Claims. (Cl. 220—9)

This invention relates to the construction of cabinets generally employed for refrigerating purposes and has particular relation to the outer wall, frame and supporting structure which such 5 cabinets ordinarily embrace, and to the method of constructing and assembling thereof.

This application is a division of my application, Serial No. 692,882, filed October 9, 1933, for "Cabinet Design", now matured into Patent 10 2,059,182 and reissued as Re. 20,610.

An object of the invention is to provide a cabinet which shall be easy to assemble, attractive in appearance, and which can be manufactured at a cost comparable with the cost of 15 cabinets of other designs now being produced.

Another object of the invention is to provide a cabinet for refrigeration purposes, the outer surface of which is covered by a shell embracing among other parts, a pair of end pieces or sections 20 which are provided with flanged edge portions projecting inwardly toward the central portion of the cabinet upon the front and upper walls thereof.

Another object of the invention is to provide a cabinet having an outer shell portion formed to 25 cover the surface thereof and embracing a pair of end sections connected at the top by a top panel covering only a portion of the upper surface of the cabinet with the remaining portion of such surface being covered by inwardly projecting portions of the panels employed for covering the ends of the cabinet.

Another object of the invention is to provide a new type of base or supporting legs for refrigerators which will provide for the latter a more 30 rigid support and at the same time will give to the appearance of the entire structure a more massive and pleasing effect.

Another object of the invention is to provide 35 for a cabinet to be employed for refrigeration purposes, a support consisting of a pair of spaced legs having a connecting portion adjacent the upper extremities thereof which will not only provide a stiffening element for the legs, but will provide a substitute for a panel member which ordinarily has been embodied in the cabinet structure supported by the legs.

Another object of the invention is to provide a 40 resilient separating member to be disposed between the lower surface of a cabinet employed in refrigeration purposes and one or more of the legs supporting the cabinet for the purpose of deadening the sound vibrations generated in the refrigerating mechanism employed in the cabinet 45 and which might otherwise be transmitted

through the cabinet legs to within the building in which the refrigerator is employed.

Another object of the invention is to provide a novel method of constructing and assembling cabinets of the type disclosed in this applica- 5 tion.

The embodiment of the invention disclosed for the purpose of illustration comprises generally a pair of end sections which, in the present instance, are formed from a single sheet of metal 10 by suitably constructed dies and each of which is provided with inwardly flanged edge portions at the upper and the front and rear edge portions thereof. The flanges at the front of the end sections aforesaid, project inwardly for the 15 purpose of covering the front surface of the cabinet beyond the door openings formed therein and at the upper extremities thereof, the flanged portions project inwardly to provide preferably a flush joint with an upper section, the forward 20 edge of which extends downwardly toward the aforesaid door openings and in such region provides for closing the space between the inwardly flanged front and upper portions of the end panels. 25

The refrigerator, if desired, may be provided with a frame of any suitable character, an insulated inner compartment for storing provisions, and a machine compartment for housing the refrigerating mechanism with which such cabinets 30 ordinarily are provided. Any number of doors may be employed for obtaining access to the interior of the refrigerated compartment and to the machine compartment employed therewith.

The legs, in the present instance, are formed 35 of stamped sheet metal and extend a considerable distance along the two sides of the cabinet adjacent each corner. The legs, however, may be formed of any suitable material and may be of any desired design. 40

At the front of the cabinet there is employed an elongated reinforcing panel which extends downwardly just below the front of the cabinet and fills the space between the two front legs. Rubber gaskets are employed between the flanged 45 upper portion of each of the legs and the lower parts of the cabinet adjacent thereto and between the front reinforcing panel and the legs and the lower part of the cabinet adjacent such panel. 50

It will be observed that a plurality of doors are employed on the front of the cabinet for the refrigerating and machine compartment and that such doors are so closely disposed together as to provide a substantially continuous panel over the 55

- entire front of the cabinet in the space within the border formed by the inwardly projecting front flanges of the two side panels and the downwardly projecting front flange of the upper panel. This construction not only saves some of the material heretofore required in finishing up the front of a cabinet, but it contributes materially to the beauty and symmetry of the entire structure.
- 10 For a better understanding of the invention, reference may now be had to the accompanying drawing forming a part of this specification, in which:
- 15 Fig. 1 is a front elevational view of a cabinet structure embracing the principles of the invention herein disclosed;
- 20 Fig. 2 is an end elevational view of the cabinet structure illustrated in front elevational view by Fig. 1;
- 25 Fig. 3 is a fragmentary horizontal sectional view of the cabinet taken substantially in the plane of line 3—3 of Fig. 1;
- 30 Fig. 4 is a fragmentary horizontal sectional view of the cabinet taken substantially in the plane of line 4—4 of Fig. 2 and looking in the direction of the arrows thereon;
- 35 Fig. 5 is a fragmentary vertical sectional view taken at one of the upper corners of the refrigerator and substantially in the plane of line 5—5 of Fig. 1;
- 40 Fig. 6 is a fragmentary horizontal sectional view taken in the plane of line 6—6 of Fig. 1;
- 45 Fig. 7 is a vertical sectional view taken through the cross-frame structure at the lower front part of the insulated compartment formed in the refrigerator and illustrating the structure as it would appear substantially in the plane of line 7—7 of Fig. 1;
- 50 Fig. 8 is a fragmentary sectional view taken substantially in the plane of line 8—8 of Fig. 1; and
- 55 Fig. 9 is a fragmentary sectional view of the base and a lower portion of the cabinet structure to which the base is secured, the view being taken substantially in the plane of line 9—9 of Fig. 1.
- 60 The cabinet 10 employed in practicing the invention consists generally of a pair of side walls 11 and 12, an upper wall 13, an intermediate wall 14 or lower refrigerating compartment wall 14 and a rear wall 16. Inside the two walls 11 and 12 and between the lower wall 14 and the upper wall 13, there is formed a heat insulated refrigerating compartment 17, and beneath the wall 14 and between the walls 11 and 12, there is a machine compartment 18 in which the condensing unit (not shown) for the refrigerating mechanism is shown. The walls of the refrigerating compartment 17 are provided with thick insulating slabs of any suitable character, and the walls of the machine compartment 18 are provided, if desired, with relatively thin sound-absorbing slabs for damping out the vibrations and noises originating in the refrigerating mechanism located therein.
- 65 The refrigerating compartment 17 may have one or more doors such as those indicated at 21 and 22. When two doors are employed, as in the present instance, there generally is provided a center post or pilaster, such as that indicated at 23, for enclosing the space between the doors and providing a solid obstruction against which the inner edges of the doors are supported. These doors normally are heat insulated, as are the 70 remainder of the walls of the refrigerating compartment 17. The front of the machine compartment 18 is enclosed by a door 24 which is substantially of the same width as are the two doors 21 and 22, and the upper edge of the door is spaced beneath the lower edges of the doors 21 and 22 by such a slight distance as to give the entire front of the cabinet the appearance of being covered by a unitary panel. Considering these doors as a unitary panel indicated generally at 26, it will be observed that the spaces beyond the sides of the panel at the upper and side extremities thereof, are substantially equal. It also will be observed that the space between the two doors 21 and 22 is substantially of the same width as the space between the lower edges of the two doors 21 and 22 and the upper edge of the machine compartment door 24.
- 75 The entire cabinet structure is supported by a base 27 consisting of front sections 28 supporting the front of the cabinet, and a pair of sections 20 or legs 29 supporting the rear of the cabinet.
- In order to provide a supporting structure for the several walls of the cabinet 10, there is employed internally thereof, a frame 31, the front portion of which is formed around the front of the cabinet to provide a door frame 32 through which the insulated refrigerating compartment 17 in the interior of the cabinet is accessible. The front and outer edges of the frame at the top and two sides of the cabinet surrounding both the refrigerating compartment 17 and the machine compartment 18 are relieved to provide a widely rounded edge indicated at 33, so that the exterior covering of the cabinet can be formed with the desired contour in such regions. At the upper corners of the cabinet there are also a pair of rearwardly extended frame members indicated at 34 and the upper outer corners of which are rounded as indicated at 35, to provide clearance for permitting the formation of the outer shell of the cabinet in such regions to provide the desired contour.
- 80 The rear of the cabinet is supported by a rear frame indicated at 36, consisting of a pair of vertical side members 37 and cross members arranged at points between the two for giving the frame the proper strength and rigidity. Various other cross members are provided between the front and rear frames 31 and 36 for the purpose of rigidly maintaining the two frames in proper relation. Inside the refrigerating compartment 17 and within the various frame members located thereabout and within the walls of the cabinet, there is disposed an inner shell or tank member 39, and the front edges of which are provided with flanges indicated at 41, which are secured with the inside edge of the front frame 31 around the door opening formed therein.
- 85 Outside of the tank 39 and between the frame members thereabout, there are employed slabs of heat insulating material indicated at 42, which tend to materially reduce the flow of heat between the interior and the exterior of the cabinet.
- 90 A top sub-panel 62, of wood or any other suitable reinforcing material, is disposed above the insulating material 42 on the top of the container 38 and is secured between the front, side, and rear top frame members and supported thereby in such a manner that the upper surface is flush with that of said frame members. Sub-panel 62 is cut 70 away at the side edges thereof to provide a groove extending across the top of the frame and which is adapted to receive flanges provided on the top and side panels of the cabinet.
- 95 For covering the exterior of the cabinet, there

is employed an outer shell or covering indicated generally at 43 and consisting principally of a pair of side panels 44 and 46, an upper panel 47 and a rear panel 48. The two side or end panels 5 44 and 46 extend from top to bottom of the cabinet, along the sides of the machine compartment 18 and the refrigerating compartment 17, and not only cover the two walls of the cabinet at the sides thereof, but also cover portions of the front, 10 top and back walls of the cabinet inside the inwardly projecting front, top and rear flanges 49, 51 and 52 thereof. These panels preferably are made of sheet metal and shaped in a die, suitable 15 for the purpose, although it is apparent that they can be formed of any desired material and by any suitable process. The inner edges of the front flanges 49 are formed with securing flanges 53 which extend inwardly of the opening to the refrigerating compartment 17 and are secured 20 to the inner edges of the door frame 31 directly opposite the flanges 41 formed on the inner shell or tank 39. All of the flanges, such as are indicated at 41 and 53, are covered by trim strips 25 indicated at 54, which are secured to the inner surface of the door frame 32 by screws 56.

The top flanges 51 and also the front edge of the front flanges 49 down to the door opening in the cabinet, are provided with inwardly projecting securing flanges indicated at 57, which 30 project into grooves formed in the insulating material and the frame of the cabinet in regions adjacent thereto.

The side panels 44 and 46 are put on the walls of the cabinet by first inserting the securing 35 flanges 53 inside the door opening and holding the remainder thereof away from the cabinet and upwardly beyond the normal position thereof, to such an extent that the upper securing flanges 57 are free to move above the upper surface of the 40 cabinet. From this position, the sections are pivoted inwardly upon the flanges 53 until the sides of the cabinet are engaged by the inward surfaces thereof, and the flange 52 is in position upon the rear cabinet wall. When the panels are 45 in this position, the flanges 57 are immediately above the grooves formed in the top of the cabinet and may thereafter be inserted therein simply by allowing the panels to slide downwardly upon the cabinet side walls. In order to prevent 50 the panels from rattling or from becoming displaced upon the frame, any number of screws, indicated at 61, may be employed along the rear and upper edges of the panels to secure them in position.

The top panel 47, which, in the present instance, is substantially of the same cross sectional contour as are the two side panels 44 and 46, also has a front flange 63 projecting downwardly across the front of the cabinet and into the door opening space therein and the lower end 55 of which is provided with an inwardly projecting securing flange 64, which is adapted to be secured around the lower surface of the upper section of the door frame 32. The rear edge of the top panel 47 also is turned downwardly, as is indicated at 66, for the purpose of engaging a portion of the back of the cabinet, as do the rear flanges 52 on the side panels 44 and 46. The opposite edges of the upper panel 47 are turned 60 downwardly and inwardly across the top and front and rear sections thereof, respectively and as is indicated at 67, to provide securing flanges 67 which are adapted to extend downwardly into the grooves formed in the top, front and rear of

the cabinet and into which the securing flanges 57 also project.

When the upper panel 47 is in position upon the upper surface of the cabinet, the flanges 67 are spaced a short distance from the flanges 57 located directly oppositely thereto, to provide spaces for receiving resilient gaskets 69. These gaskets, which may be formed of any suitable kind of soft and resilient material, are preferably formed with an outer meet portion 71 and an inner lock portion 72, which is adapted to project around the inner extremities of the flanges 67 and between which portions there is provided a web portion 73 which is adapted to retain the flanges 57 and 67 in properly spaced relation. The upper panel 47 is placed in position somewhat like the side panels 44 and 46, by inserting the securing flange 64 beneath the lower edge of the upper member of the frame 32 and then moving the rear of the panel downwardly until the rear flange 66 is in position beside the flanges 57. The gasket 69 is placed in position upon the flanges 67 before the top panel is moved into position, and consequently the gaskets slide downwardly into position between the flanges 57 and 67 as the top is moved into place.

It will be observed that the cabinet has the appearance, from the front sides and top thereof, of being constructed principally of three pieces consisting of the side panels 44, 46 and the top 30 panel 47 and a plurality of doors covering substantially the entire front of the cabinet except for the space thereabout formed by the front flange portion of the top and two sides aforementioned. The top panel 47 is so formed and moved 35 into position as to form substantially flush joints with the upper extremities of the two end panels 44 and 46, thus giving the cabinet a pleasing appearance characterized by a classic simplicity of design.

The back of the cabinet can be covered by an ordinary flat covering such as that indicated at 48, and the outer edges of which are secured in any suitable manner inside the flanges 52 of the side panels 44 and 46 and the flange 66 of the top panel 47.

In the present instance, the doors 21 and 22 of the refrigerating compartment 17 and the door 24 of the machine compartment 18 are positioned in such manner as to extend outwardly a slight distance down the front of the cabinet to provide an outwardly projecting paneled effect, although it is apparent that the doors may be put on in any other desired manner without materially changing the appearance of the entire structure.

The base 27, consisting of the front section 28 and the two rear sections 29, normally is secured upon inwardly projecting flanges 76 formed along the upper edges of the parts, and between these flanges and the cabinet there are disposed a plurality of beaded rubber gasket sections indicated generally at 77. The front section 28 of the base consists of a pair of massive legs 79 and 81, and between which there is connected, with suitable rubber gaskets 82 and 83 at opposite ends thereof, a spacing panel or skirt 84. Adjacent the central portion of the panel 84 there is formed, outwardly from the rest of the surface thereof, a projection 86, the surface of which 70 is set at an angle to the vertical surface of the cabinet and base adjacent thereto, to provide a region where the name of the product may be easily seen by anyone standing in front of the cabinet and looking downwardly. The spacing

panel 84 is secured to the adjacent edges of the legs 79 and 81 by bolts 87 which are adapted to compress the gaskets 82 and 83 between flanges 89 and 91 formed at the adjacent edges of the aforesaid parts. It is preferable to provide practically all of the edges of the two legs 29, the legs 79 and 81, and the spacing panel 84, with rearwardly extending flanges on both the upper and lower extremities thereof and on intermediate edges therebetween, in order to provide the base structure with adequate structural strength and in addition, to give the entire base a rugged and massive appearance. Where the doors on the front of the cabinet project outwardly thereof, as do the doors in the cabinet 10, disclosed herein, it may be desirable to provide the front face section with a forwardly projecting portion indicated at 93, in the region thereof just below the lower edge of the machine 15 compartment door 24. This position of the space carries out the general paneled effect formed by the doors in the front surface of the cabinet and prevents the doors from having the appearance of overhanging the base.

25 The frame structure, insulation, inner and outer coverings, the doors and the base, all may be manufactured as separate units and assembled in production in such manner that any part may be taken off and replaced, in the event it should 30 appear defective or become damaged in any way. For cooling the refrigerating compartment of the cabinet, any desired type of refrigerating mechanism may be employed, and the heat dissipating unit for which may be located in the machine 35 compartment of the cabinet or wherever else desired.

It is to be understood that the invention is not limited to the specific features of the structure disclosed, but is to be considered broadly as is represented by the scope of the appended claims.

I claim:

1. The method of constructing a heat insulated cabinet, having a top wall, an end wall and a front wall the latter being provided with 45 a door opening therein, which comprises forming grooves in said top and front walls substantially in alignment with one of the edges of said door opening, forming an end panel member to provide a continuous flange extending laterally 50 thereon for covering a portion of said top and front walls in addition to said end wall and securing flanges extending inwardly from the extremities of said covering flanges for engagement within said grooves and door opening, then 55 inserting said front securing flange in said door

opening with said upper covering flange elevated above said top wall to permit free movement of said top securing flange across said top wall, then moving said panel angularly until the inner surface thereof engages the outer surface of said 5 end wall, and then sliding said panel downwardly until said top securing flange is confined within a grooved portion of the surface of said upper wall.

2. The method of constructing a cabinet which 10 consists in forming a substantially rigid frame work having a top wall, an end wall, a front wall provided with a door opening therein, and a three sided corner forming at the juncture of said walls, forming grooves in said top and front 15 walls substantially in alignment with one of the edges of said door opening, forming an end panel member to provide a continuous flange extending laterally thereof for covering a portion of the top and front walls and the three sided corner 20 in addition to the end wall and securing flanges extending inwardly from the extremities of said covering flanges for engagement with said grooves and door opening, then inserting said front securing flange in said door opening with 25 said upper covering flange elevated above said top wall to permit free movement of said top securing frame across said top wall, then moving said panel member angularly until the inner 30 surface thereof engages the outer surface of said outer wall, and then sliding said panel downwardly until said top securing flange is confined within a grooved portion of the surface of said upper wall.

3. The method of constructing a heat insulated cabinet having a top wall, an end wall and a front wall which comprises providing securing grooves in said top and front walls, forming an end panel member to provide a continuous flange extending laterally thereon for covering a portion of said top and front walls in addition to 35 said end wall and securing flanges extending inwardly from the extremities of said covering flanges for engagement with said securing grooves, then inserting said front securing flange 45 in said front wall securing groove with said top wall covering flange elevated above said top wall to permit free movement of said top securing flange across said top wall, then moving said panel member angularly until the inner surface 50 thereof engages the outer surface of said end wall, and then sliding said panel downwardly until said top securing flange is engaged with said securing groove of said top wall.

LEONARD H. DARBYSHIRE. 55
